ACNE SKIMMER

Genevieve M. Jones, 10840 E. 85th Ave.,
Portland, Oreg. 97266

Filed Mar. 10, 1969, Ser. No. 16,162

Term of patent 14 years

Int. Cl. D28—01

U.S. Cl. D83—12

Fig. 1

Fig. 2

Fig. 3

Fig. 5

Fig. 4

Fig. 6

I claim:

The ornamental design for an acne skimmer, substantially as shown and described.
